CHAIR CONVERTIBLE INTO A TABLE AND
VICE VERSA

Ruby S. Vella, Los Angeles, Calif.

Application May 2, 1950, Serial No. 159,522

3 Claims. (Cl. 155—43)

1

This invention relates to an interconvertible combination table and chair.

More specifically speaking the invention pertains to a piece of furniture convertible from an arm chair into a table and vice versa, the table top member forming a back rest when the device is in use as a chair, and the arms of the chair supporting the table top member when the device is used as a table.

Although the art to which this invention pertains is already well developed, yet there remains room for improvement, particularly in regard to simplifying construction and to securing a smoother, more satisfactory operation of such a device.

Accordingly, among the objects of the present invention are: to reduce the number of parts in the device, and to provide a device consisting of a set of cooperating parts which can be assembled in a novel, more satisfactory manner.

A more specific object is to provide a combination chair back and table top member wherein the back of the chair is provided with studs projecting from its opposite edges, said studs slidably cooperating in an advantageous manner with internal, oppositely facing, guide grooves provided in the arms of the chair, so that the member which selectively forms the back of the chair and the table top can be operated in a more satisfactory manner in converting the chair into a table and in converting the table into a chair.

Another object is to provide the device with a pair of arm rests each having a longitudinal groove facing that of the other and a depression in the front end of each of said grooves; in combination with a chair back member with pins projecting from its side edges to travel in said grooves, so positioned in relation to said grooves and depressions as to maintain said member when horizontal out of injurious frictional contact with said arm rests except when it is in its most forward position, at which time said pins seat in said depressions and lower the side portions of said member into contact with said arm rests, while releasably holding the table top against backsiding.

Referring to the accompanying drawing, which illustrates a preferred embodiment of the invention, now reduced to practice,

Fig. 1 is a side elevation of the device, the swingable member being shown in full lines adjusted to the chair back forming position and in dotted lines adjusted for use as a table top.

Fig. 2 is a front elevation of the device, the

2

swingable member being shown in full lines adjusted to the table top forming position and in dotted lines in the chair back forming position.

Fig. 3 is a perspective view, on an enlarged scale, parts being broken away so that the observer sees only the back portion of the device adjusted to the chair forming position. A corner portion of the chair back cover is forwardly deflected to disclose underlying structure.

Referring in detail to the drawing, and first considering more particularly the chair feature of the invention, the chair bottom 5 is shown including a substantially rectangular open or skeletal frame 6 supported in its corner portions by upstanding front legs 7 and rear legs 8, the midlength portions of these four legs being nailed or otherwise secured to corner portions of said chair bottom frame, which is provided with a conventional, padded seat portion 6a.

20 Twin horizontal arm rests 10 are provided, each of which is secured atop the legs 7 and 8 at its side of the chair, a rear end portion 10a of each of said arm rests extending rearwardly of a back chair leg 8. Each of said arm rests is internally grooved as indicated at 11, from a point about a third the way back from its front end, rearwardly to a point considerably back of the rear leg 8 at its side of the device, each groove being rectangular in cross section and preferably extending about half way through the thickness of the arm rest, as is well shown in Fig. 3.

25 A combined, swingably mounted chair back and table top member 15 is provided, said member carrying a substantially rectangular, padded back rest proper 16 having side pieces 17 which are spaced inwardly from the outer edge portions of the body portion of said swingable member 15. Each of said side pieces 17 carries an outwardly projecting dowel pin or stud 18 at all times projecting slidably into the arm rest groove 11 at its side of the chair. Said pins 18 are located somewhat above the mid-height of said member 15 when the latter is in its chair back forming position at which time, owing to said pins 18 being located forwardly of its center of gravity, said member 15 inclines slightly backward with its pins 18 engaging the rear ends of the grooves 11 and its lower end abutting a pair of elastic bumpers 19 carried by the legs 8. The lower end of said member 15 may be swung upwardly and rearwardly from the chair back forming position, and during such swing thereof said pins 18 remain in engagement with the 30 rear ends of the guide grooves 11 until said mem-

ber 15 has reached a nearly horizontal position, whereupon the operator will pull said member 15 forwardly till its pins 18 seat in bottom depressions 11a provided for them at the front ends of said grooves, at which time the laterally projecting side portions of the member 15, which form ledges 20, will rest upon the entire upper surface portions of the arm rests 10 by reason of the pins 18 having dropped into the aforesaid depressions 11a.

The rear end portions of the arm rests 10 are rounded at 21, being substantially semicircular as viewed in side elevation, so as to present smooth surfaces toward the aforesaid ledges 20 as their upper ends swing downwardly and forwardly over said rounded arm rest portions when converting the device from a chair into a table, and when converting it from a table into a chair swing backwardly and upwardly over said rounded parts. During these operations said ledges do not contact with the upper surface of said arm rests; therefore injurious wear and friction is avoided.

The superior manner in which the device is operable will be more clearly understood when it is noted that, at each side of the device, when the stud 18 is in engagement with the rear end of the groove 11, the radial distance from the center of the stud to the adjacent part of the ledge 20 is slightly greater than the vertical distance from the midheight of the groove to the top of the arm rest, so that when the lower end of member 15 is swung upwardly and rearwardly from its pendant position about the axis of said stud until said member reaches a horizontal position and thereupon is pulled forwardly toward proper table top forming position, during this operation a clearance can be maintained between said ledge 20 and the top surface of the arm rest until said member 15 has been pulled so far forward as to cause its stud 18 to drop into the depression 11a. Therefore, in operating the device forward and rearward horizontal movement of said member 15 will not produce injurious abrasion or wear between it and the underlying arm rests, and yet when it is in its most forward position it will rest in a flatwise, non-tiltable manner upon the arm rests and will be releasably locked against backsiding.

In Fig. 3 the body portion of the chair back member 15 is shown projecting above the padded back rest, where it is ornamented by filigree openings 26 and a wavy upper edge 27.

In assembling the device, after the padded back rest member 16 has been attached to the remaining part of the swingable member 15 and the pins 18 have been driven into place with bores provided for them into which they snugly fit, the grooves 11 in the arm rests are caused to register with said pins while the swingable member 15 is in a superjacent relation to the tops of the four chair legs. Whereupon the arm rests are put into place atop said legs.

It is to be understood that the form of the invention herein illustrated and described is but one example of the same and that various changes as to the shape, size and arrangement of parts may be resorted to without departing from the spirit of the invention or the scope of the subjoined claims.

I claim:

1. An interconvertible combination table and chair having a pair of substantially horizontal arm rests in each of which is a longitudinal groove facing the other arm rest, and a chair

back member with outwardly projecting pins in its side edges at all times occupying said grooves to guide said member into and from table top forming position, said grooves each having a depression at its outer end, the spacing of said pins from the under side of the table top compared to the spacing of the grooves from the top faces of the arms maintaining the side portions of said member out of sliding contact with the upper surfaces of said arm rests during the movement of said member from chair back to table top position, and vice versa, and when said member is in its most forward table top forming position said depressions providing seats for said pins which enable the operator to lower said member into a contact with said arm rests wherein it is releasably held against backsiding.

2. A combination chair and table comprising a stationary frame including legs and a rectangular chair bottom supported by said legs, there being a front and a rear pair of said legs connected with corner portions of said chair bottom and extending upwardly thereabove, a substantially horizontal arm rest supported at each side of the chair atop the aforesaid upwardly extending portions of said legs, each of said arm rests having a rear end portion which extends a considerable distance rearwardly of the top of the rear leg at its side of the chair, each of said arm rests having along it a longitudinal groove the open side of which is directed toward the opposite arm rest and which extends from a point considerably spaced away from the front end of the arm rest rearwardly to a point considerably rearward of the top of the rear leg at that side of the chair, and a combination chair back and table top member, said member carrying at each side an outwardly projecting pin which, when said member is in chair back forming position is located forwardly of the center of gravity of said member and above its midheight and engages the rear end of the aforesaid groove at its side of the chair while the lower end of said member inclines forwardly and abuts loosely against the back side of the aforesaid stationary frame, said member being swingable upwardly at its lower portion and movable forwardly, thus advancing its said pins along said guide grooves until the former occupy the front end portions of the latter, said member having laterally projecting side portions which at such time rest upon said arm rests, said grooves each having a bottom depression in its front end, the spacing of said pins from the under side of the table top compared to the spacing of the grooves from the top faces of the arms maintaining said laterally projecting side portions of said member out of contact with the upper surfaces of said arm rests except when said member is in its most forward position, at which time said pins seat in said depressions and permit said side portions to lower into contact with the arm rests.

3. A chair having legs, a seat portion carried thereby, arm rests mounted upon said legs and a back portion for said chair convertible into a table top and vice versa, a side piece secured to said back portion in an inwardly spaced relation to each of its side edges, a dowel pin anchored in each said side piece and having a free end portion extending outwardly therefrom, there being a groove in each said arm rest facing the other arm rest and extending from a point near the rear end of the arm rest to a point in a predetermined relation to its front end, said pins occupying said grooves in both the back forming position of the chair back and in the table forming

position, said pins when said back is in the chair back forming position occupying the rearmost position in said grooves and when said back is in the table forming position said pins occupying the foremost position in said grooves, that portion of said chair back which lies adjacent said dowel supporting side pieces and which in the table forming position overlie said arm rests comprising ledges, the distance from each said ledge to the center of each said pin being slightly greater than the vertical distance from the mid-height of said grooves to the topmost portion of said arm rests, whereby as said pins move in a horizontal direction in said grooves said ledges remain out of contact with said arm rests, each of said grooves having at its front end a depres-

5
6
sion which when said pins are seated therein lowers said ledges into contact with the upper surfaces of said arm rests.
